CLAIM

I claim the ornamental design for a shoe, as shown and described.

DESCRIPTION

FIG. 1 is a front perspective view of a shoe, showing my new design;

FIG. 2 is a left side view thereof; and,

FIG. 3 is a rear perspective view thereof.

The dot-dash broken lines represent boundaries of the claimed design and form no part thereof. The broken lines depicting the remainder of the shoe show features no part of the claimed design.
